UNITED STATES PATENT OFFICE.

JAMES BARKER, OF DETROIT, MICHIGAN.

TRIAL OR BALANCE SHEET.

1,072,417.

Specification of Letters Patent.

Patented Sept. 9, 1913.

Application filed May 18, 1911. Serial No. 627,989.

To all whom it may concern:

Be it known that I, JAMES BARKER, a citizen of the United States of America, residing at Detroit, in the county of Wayne and 5 State of Michigan, have invented certain new and useful Improvements in Trial or Balance Sheets, of which the following is a specification, reference being had therein to the accompanying drawings.

10 My invention relates to trial or balance-sheets divided into complementary sections for the accounts and names respectively, and to that type of trial or balance-sheet in which one of the sections is provided with 15 an erasing surface permitting the ready erasure of the names or figures thereon.

The invention consists in a detachable portion for the leaf which may be readily engaged therewith or disengaged therefrom, 20 in a transparent protecting strip or covering for the detachable portion, and further in the novel construction and arrangement of the several parts of the leaf as will be more fully hereinafter described and particularly pointed out in the claims.

In the drawings, Figure 1 is a plan view of a leaf embodying my invention; Fig. 2 is a fragmentary perspective view partly in section thereof; and Figs. 3 and 4 are enlarged sections on the line $y-y$ and $x-x$ 30 respectively of Fig. 1.

The opposite sides or faces of the sheet or leaf A are each divided in the usual manner, into an account section a and a name section b , the corresponding sections upon opposite sides of the leaf being alternated. Preferably the account sections are provided with erasing surfaces, such as celluloid strips c glued or cemented to the sections 40 a . In the usual construction of this type of leaf the names are written directly upon that portion of the face of the leaf forming the name section and while the erasing surface for the section a permitted the accounts to be altered, the names could not be changed without defacing the leaf.

With my improved construction exchangeable name slips or cards B are provided for the sections b and to change the 50 names upon either side of the leaf it is merely necessary to substitute a new card or slip, having thereon the names desired, for the card in engagement with the leaf. Arranged over the sections b are strips C fastened at their top and bottom edges to the leaf and forming with the latter a pocket

within which the cards are positioned. These strips are of a size to completely cover the name section and are formed of transparent material, preferably celluloid, so as to permit the names on the card therebeneath to be visible. The ends of the strips C may be secured to the leaf in any desirable manner, but in the construction illustrated, the top and bottom edges of the leaf are provided with binding strips d connected to the leaf by stitching e , the stitching passing through the ends of the transparent strips. The binding is also cemented for a portion of its length to the face of the account section and for the remaining portion to the strips C, forming shoulders f at the junction of the account and name sections, which serve as abutments for the inner edge of the cards.

The name strips or cards B are of substantially the same width as the sections b but are of a length slightly less than the distance between the stitching at the top and bottom of the leaf. As shown in Fig. 2 50 the card B is engaged with the leaf by being inserted laterally beneath the longitudinal edge g of the transparent strip, the stitching positioning the card longitudinally and the shoulders f laterally.

It is customary for the figures on the account section to be made with pencil and as the name and account sections upon opposite sides of the leaf are alternated, if the writing on the name section is exposed, the 90 pencil on the account section of one leaf tends to blur the writing on the name section of the adjacent leaf. This objection is eliminated by my improved construction since the writing on the name cards is protected by the strips C, and also as the surface of the celluloid strip C is very smooth, the blurring of the figures on the account section is prevented.

What I claim as my invention is:

1. A trial or balance sheet having each of its faces divided into complementary sections, one of the sections having an erasing surface, a transparent strip arranged over the other section and having its ends secured 105 to the sheet forming with the latter a pocket, and a card detachably slidably engaging the pocket, the corresponding sections upon opposite faces of the sheet being alternated.

2. A trial or balance sheet having each of its faces divided into complementary sec-

5 tions, one of the sections having an erasing surface, a transparent strip arranged over the other section and secured to the sheet forming therewith a pocket, a card detachably slidably engaging the pocket, and a binding at the top and bottom edges of the sheet serving as a means for positioning the card.

10 3. A trial or balance sheet having the face thereof divided into complementary sections, an erasing surface permanently secured to one of the sections, a transparent strip arranged over the other section and attached to the sheet forming therewith a pocket, and a card detachably slidably engaging the pocket.

15 4. A trial or balance sheet having the face thereof divided into complementary sections, one of the sections having an erasing

surface, a slip or card detachably engaging 20 the sheet and positioned over the other section, and a covering of transparent material for the detachable slip permanently secured to the sheet.

25 5. A trial or balance sheet having the face thereof divided into complementary sections, one of the sections having an erasing surface; a slip or card upon which names are adapted to be written, detachably engaging the other section, and a transparent cov- 30 ering for the detachable strip secured to the sheet.

In testimony whereof I affix my signature in presence of two witnesses.

JAMES BARKER.
